International Search Report for PCT/US08/54212 mailed Jun. 25, 2008.

Primary Examiner — Ian Simmons*Assistant Examiner* — Dana L Sipos(74) *Attorney, Agent, or Firm* — Ungaretti & Harris LLP(57) **CLAIM**

I claim the ornamental design for a container body, as shown and described.

DESCRIPTION

FIG. 1 is a perspective view of the present invention;

FIG. 2 is a side view of the present invention;

FIG. 3 is a top view of the present invention; and,

FIG. 4 is a bottom view of the present invention.

Features shown in broken lines in the drawings are not part of the claim.
